UNITED STATES PATENT OFFICE

120,809

DESIGN FOR A COMFORTABLE

Lawrence Goodstein, New York, N. Y.

Application May 4, 1940, Serial No. 92,156

Term of patent 3½ years

To all whom it may concern:

Be it known that I, Lawrence Goodstein, a citizen of the United States of America, residing in New York city, in the Borough of Manhattan, county and State of New York, have invented a new, original, and ornamental Design for a Comfortable, of which the following is a specification, reference being had to the accompanying drawing, forming part thereof, wherein the figure is a plan view of a comfortable showing my new design.

The rear of the comfortable is substantially plain.

I claim:

The ornamental design for a comfortable, substantially as shown, and described.

LAWRENCE GOODSTEIN.
